UNITED STATES PATENT OFFICE

156,343

SAUCEPAN

Floyd C. Jewell, Long Beach, Calif., assignor, by mesne assignments, to Crown Jewel Ware, Inc.,
Dallas, Tex., a corporation of Delaware

Application August 15, 1947, Serial No. 140,901

Term of patent 14 years

(Cl. D44—1)

To all whom it may concern:

Be it known that I, Floyd C. Jewell, a citizen of the United States and residing at Long Beach, in the county of Los Angeles, State of California, have invented a new, original, and ornamental Design for a Saucepan, of which the following is a specification, reference being had to the accompanying drawing, forming part thereof, in which:

Fig. 1 is a top plan view of a saucepan, showing my new design,

Fig. 2 is a side elevation thereof, and

Fig. 3 is an elevational view of the saucepan taken at right angles to Fig. 2 with the lid turned around to show the face of the lid knob which is in line with the handle.

The dominant features of the present design reside in the knob and handles in conjunction with the saucepan as shown.

I claim:

The ornamental design for a saucepan, substantially as shown and described.

FLOYD C. JEWELL.
